UNITED STATES PATENT OFFICE.

CHRISTOPHER FLINN, OF TERRE HAUTE, INDIANA, ASSIGNOR TO AMERICAN CAR AND FOUNDRY COMPANY, OF ST. LOUIS, MISSOURI, A CORPORATION OF NEW JERSEY.

TANK-CAR.

1,122,378.

Specification of Letters Patent. Patented Dec. 29, 1914.

Application filed September 14, 1911, Serial No. 449,632.

To all whom it may concern:

Be it known that I, CHRISTOPHER FLINN, residing at Terre Haute, Vigo county, Indiana, and being a citizen of the United States, have invented certain new and useful Improvements in Tank-Cars, of which the following is a full, clear, and exact description, such as will enable others skilled in the art to which it appertains to make and use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings: Figure 1 is a side elevational view of a tank car constructed in accordance with this invention, the trucks being omitted. Fig. 2 is a top plan view, parts being broken away and shown in section on the plane of line 2—2 of Fig. 1. Fig. 3 is an enlarged vertical transverse sectional view taken on the plane of line 3—3 of Fig. 1. Fig. 4 is a further enlarged fragmentary elevational view, partly in section, of one of the tank supports and adjacent parts. Fig. 5 is an enlarged detail sectional view taken on a plane of line 5—5 of Fig. 3. Fig. 6 is a transverse vertical sectional view through the underframe employed, said section being taken substantially on the plane of line 6—6 of Fig. 4, and Fig. 7 is an inverted plan view of one of the tank supports and its connections with the under side of the tank, the underframe being omitted.

This invention relates to tank car construction and is particularly designed to overcome the destructive effects incident to the coupling of cars and to other similar collisions. It provides that the tank shall have a limited and easy motion longitudinally of the underframe for absorbing such shocks, and it is so designed that the weight of the tank, and of the lading carried thereby, is utilized to limit the elasticity of the connection between tank and underframe.

In the preferred structure illustrated the tank 1 is provided, at each end, with a pair of saddle brackets as 2—2, they being fixed to the under surface of the tank upon opposite sides of the median line thereof. Other brackets 2 may be positioned intermediate

the ends of the tank if desired. Each bracket 2 is formed with an upper flange as 2^a shaped to the curvature of the tank, and each pair of brackets is connected, across the bottom of the tank, by a tie plate 3. The tie plates 3 are fitted to the curvature of the tank and each pair of brackets 2, with the connected tie plate 3 forms a cradle in which the tank rests.

Inside of the tank, at the point of each of the cradles, is a reinforcing diaphragm 4, said diaphragm comprising a web plate 5 with reinforcing angles 6—6 fixed to its upper edge and with reinforcing angles 7—7 fixed to its bottom edge, the bottom edge of the plate and the ends of the angles 7—7 being curved to fit the tank. The outstanding flanges of the curved portions of the reinforcing angles 7 are riveted, through the tank shell, to the flanges 2^a of the saddle brackets 2.

A relatively wide top cover plate 8 is fixed to the outstanding flanges of the reinforcing angles 6 and has its opposite ends bent upwardly against the sides of the tank and fixed by through rivets, to the upper ends of the flanges 2^a—2^a of the brackets 2—2.

The tank cradles are movably suspended above the underframe by pivotal connections between said cradles and the underframe. These connections being identical at each of the saddle brackets 2 one only need be described in detail as follows: At the lower outer corner of each of the saddle brackets 2 is formed a socket as 9 adapted to receive a separately formed pin or trunnion 10, a suitable locking pin 11 being employed for preventing accidental displacement of said trunnion.

A bearing as 12 formed at the lower end of a link 13 is adapted to receive the trunnion 10, said link being formed, at its upper end, with a bearing 14 adapted to receive a trunnion 15 projecting from the enlarged head 16 of a support 17, and held therein by a locking pin 18 similar to the locking pin 11.

The saddle bracket 2 is formed with a vertically disposed end flange 2^b, said flange tapering from its upper edge downwardly to the socket 9 and having its outer flat face arranged in a plane extending longitudinally of the underframe. The support 17 comprises a vertically disposed web, the in-

ner face of which stands parallel to the outer face of the flange 2^b and said web is tapered upwardly from a relatively broad base 17^a to the head 16, the base 17^a being secured to the upper part of a bolster hereinafter described. The link 13, in its oscillations about the trunnion 15, is therefore, at all times, maintained between two confining walls, the heads of the trunnions 10 and 15 practically engaging said walls and serving to prevent lateral movement of the tank. From the drawings, and from the above description, it will be apparent that the tank is held in floating cradles bodily supported directly at the lower ends of a series of swinging links pivotally connected at their upper ends in rigid supports fixed to the car underframe, and that while these supporting links depend normally vertically, they are free to oscillate for permitting the desired end-wise movement of the tank.

When a blow is struck the end of the underframe, as in coupling, the underframe will move longitudinally beneath the tank causing the tank to swing on its supports and the oscillatory motion thus set up will continue after the shock, and without effect upon rivet connection between the tank and its cradles, until the momentum of such oscillation is entirely spent and the tank hangs again in normal position.

The details of construction of the underframe are not essential elements of this invention except in so far as they provide a substantial foundation for the supports 17 fixed to the upper surface thereof and any structure providing the necessary rigidity may be employed in connection with the invention without departing from the scope thereof.

The underframe structure illustrated comprises bolsters 19, center sills 20, side sills 21, end sills 22, floor plate 23, and suitable diagonal braces 24. Each of the bolsters 19 comprises a centrally disposed web plate 25 with top reinforcing angles 26 and bottom reinforcing angles 27, said web plates being fixed to the center sills by suitable angle brackets 28 and to the side sills by angle brackets 29. A bottom cover plate 30 extends beneath the center sill and is fixed to the under surfaces of the reinforcing angles 27. The usual center bearing plate 31 is fixed to the under surface of the cover plate 30 intermediate the ends thereof.

The bolster diaphragm 25 is preferably arranged centrally beneath the median line of the super-posed tank supports, and supplemental bolster members 34, comprising diaphragms 35, are spaced equi-distant forward and rearward thereof, at points substantially coincident with the forward and rearward edges of the supports 17, and each diaphragm 35 is provided with a reinforcing angle 36 fixed, preferably, directly to

the base 17^a of said supports by through rivets. A suitable reinforcing angle 37 is fixed to the lower edges of the diaphragms 35 and suitable angle brackets 38 and 39 serve to connect said diaphragms to the side 70 and center sills respectively.

A suitable bed plate as 40, if desired, may be fixed to the upper surface of the floor plate 23, said bed plate extending from the supports 17, at one side of the car, across 75 the center sills, and to the support 17 at the opposite side of the car, and extending beneath the bases 17^a of said supports.

A guard rail as 41 may be employed to advantage for the protection of trainmen. 80

In practice the operation of this construction in maintaining the relationship between the tank and underframe is accomplished by yieldingly connecting the tank with the underframe below the center of gravity of 85 said tank, and utilizing the fluctuating level of the liquid lading to maintain the equilibrium of the tank relatively to the underframe and supports. In other words, if there be any liquid in the tank it will necessarily be above the suspension of the tank, as such suspension is located below or on a line with the bottom of the tank, or below the center of gravity thereof, and any buffering or tension strain, any jar from track 90 irregularities; or in fact, any extraneous jar to the underframe or tank, even the weight of a person on the tank, would tend, when there is any lading in the tank, to move the tank longitudinally, and by so doing the 95 level of the fluid lading would be changed relatively to the bottom of the tank, or would flow toward the end of the tank opposite the application of weight or shock, with the consequent compensating action at 100 that end of the tank and a corresponding equalizing by the weight of the shifting lading corresponding to the weight or shock applied, and also a consequent limitation of the movement of the tank in a direction 105 away from the weight or shock, or as it might be termed, by a tendency to maintain the equilibrium of the tank by causing the center of stability and the center of gravity 110 to maintain themselves in the same vertical 115 plane relatively to the centers of support, or to the underframe.

I claim—

1. In a tank car, an underframe including rigid bolsters, a tank cradle pivotally connected with said underframe in vertical alignment with said bolsters, and a tank resting in said cradle. 120

2. In a tank car, an underframe including rigid bolsters, a pair of tank cradles supported above said underframe, means extending upwardly from said underframe lapping the opposite ends of said cradles and having link connection with said cradles whereby said cradles are permitted a 125 130

limited movement relative to said underframe, and a tank resting in said cradles.

3. In a tank car, an underframe comprising rigid bolsters formed with tank supports, and tank cradles pivotally connected to said supports.

4. In a tank car, a tank, an underframe, supports projecting from said underframe on opposite sides of said tank, and a pair of links each comprising a vertically disposed supporting element having opposite ends pivoted to said tank and supports above the bottoms thereof.

5. In a tank car, a cross bearer, a pair of transversely spaced supports carried thereby, a tank supporting cradle disposed between said supports and limited in its transverse movement thereby, and a connection between each of said supports and said cradle permitting limited longitudinal movement of said cradle.

6. In a tank car, an underframe, pairs of transversely spaced supports secured thereto, a bearing at the upper end of each of said supports, a depending link pivoted to each of said bearings, a cradle adapted to receive a tank positioned between said links and pivoted thereto below said bearing.

7. In a tank car, a cylindrical tank, a transversely disposed cradle affixed to the underside of said tank and extending downwardly therefrom, a reinforcing plate within said tank fastening thereto, forming in effect a continuation of said cradle, and acting as a baffle for the liquid lading in said tank.

8. In a tank car, a cylindrical tank, a transversely disposed cradle affixed to the underside of said tank and extending outwardly therefrom, a reinforcing plate within said tank fastened thereto and forming in effect a continuation of said cradle, and means pivoted to the outer lower portion of said cradle rockably supporting said tank.

9. In a tank car, bolsters, cradles rockably mounted above said bolsters, a tank on said cradles, and reinforcing plates within the tank vertically above the bolsters.

10. In a tank car, an underframe, a tank, cradles fastened to the tank and pivotally mounted on the underframe, spaced supports for said cradles at each side of the underframe, and a supporting tank between each support and an adjacent part of the cradle.

11. In a tank car, a tank, a cradle supporting the same, and baffle plates within the tank, said plates extending at an angle to each other, and one of said plates forming in effect a continuation of the cradle.

12. In combination, an underframe, a plurality of tank supports rising therefrom, links pivotally connected with said supports, tank saddles supported by said links,

and a tank rigidly connected with said saddles.

13. In a tank car, an underframe including a main bolster diaphragm and a supplemental bolster member disposed on opposite sides of said main bolster diaphragm, a tank support comprising a vertical web disposed above said main bolster diaphragm, and a broad base spanning the space between and supported by said supplemental bolster members.

14. In a tank car, an underframe, rigid means disposed above the plane of said underframe adapted to form a support for a tank, links pivoted to said means, and a tank supported by said links.

15. In a tank car, a tank, an underframe, rigid means extending vertically upwardly from said underframe upon opposite sides thereof, and swinging links pivotally connected with said rigid means and with the tank.

16. In a tank car, a tank, tank cradles, an underframe, means disposed above the plane of said underframe, and swinging links forming connections with said tank cradles adapted to permit limited endwise movement of said tank.

17. In a tank car, a tank, an underframe, and pivotally connected rigid and swinging means extending above the plane of said underframe and having pivotal connection with said tank whereby said tank is permitted endwise movement.

18. In a tank car, a tank, an underframe, rigid means extending upwardly upon opposite sides of said tank, pivotal connections therefrom to the under side of said tank adapted to permit the tank to swing and retain said tank against excessive endwise movement.

19. In a tank car, an underframe, a tank support, a cradle and pivotal connections between said support and cradle, and a swinging tank supported above said underframe.

20. In a tank car, a swinging tank, an underframe, tank cradles supported thereon, and a plurality of shock absorbing members pivotally engaging between said cradles and underframe adapted to permit limited longitudinal movement of the tank with relation to said underframe.

21. In a tank car, an underframe, a tank, tank cradles, and a plurality of pivotally connected shock absorbing members disposed upon opposite sides of said underframe having pivotal engagement with said cradles.

22. In a tank car, an underframe, a floating link-supported cradle carried thereby, and a tank resting in said cradle and adapted to swing on said links.

23. In a tank car, an underframe, a plurality of floating cradles supported upon

said underframe, means for supporting said cradles pivotally connected thereto and to said underframe, and a tank supported in said cradles.

5 24. In a tank car, an underframe, tank cradles, rigid supporting means fixed to said underframe lapping the opposite ends of said cradles, means having pivotal connections therewith, and a tank resting in 10 said cradle.

15 25. In a tank car, an underframe, a pair of tank cradles supported above said underframe, supporting means extending upwardly from said underframe lapping the 20 opposite ends of said cradles and pivotal connections between said cradles and supporting means, and a tank resting in said cradles.

25 26. In a tank car, an underframe, rigid supports thereon, floating cradles swingingly carried by said supports, a tank resting in said cradles, and a reinforcing member within a tank adjacent said cradle.

27. In a tank car, an underframe comprising bolsters, and independently movable

tank cradles comprising pivoted links and rigid supports fixed to said bolsters.

28. In a tank car, an underframe comprising bolsters, vertical tank supports, a tank, and pivotal connections between said 30 tank and said supports adapted to permit limited oscillation of the tank.

29. An underframe including bolsters, rigid supports extending above the top plane of the bolsters, links pivotally connected with said supports, cradles carried by the links and a tank supported by and connecting said cradles. 35

30. In a tank car, an underframe comprising body bolsters, supporting means extending above the top plane of said bolsters, links carried by said supporting means, and cradles adapted to receive a tank supported by said links. 40

In witness whereof I have hereunto set 45
my hand in the presence of two witnesses.
